UNITED STATES PATENT OFFICE.

RAY H. MANSON, OF ELYRIA, OHIO, ASSIGNOR TO THE DEAN ELECTRIC COMPANY, OF ELYRIA, OHIO, A CORPORATION OF OHIO.

INTERCOMMUNICATING TELEPHONE SYSTEM.

984,686.

Specification of Letters Patent.

Patented Feb. 21, 1911.

Application filed May 29, 1907. Serial No. 376,420.

To all whom it may concern:

Be it known that I, RAY H. MANSON, a citizen of the United States, residing at Elyria, in the county of Lorain and State of Ohio, have invented certain new and useful Improvements in Intercommunicating Telephone Systems, of which the following is a specification, reference being had therein to the accompanying drawing.

10 My invention relates to intercommunicating telephone systems, and consists in the arrangements and combinations hereinafter described and claimed.

An object of my invention is to provide a 15 telephone system of the class named, with indicating keys for switching the stations, to take the place of the ordinary forms of connecting cords with their necessary plugs and jacks, or, where these parts are not used, to 20 obviate the objections arising out of the use of the ordinary switches for putting into communication the various parties on the line.

With this and other ends in view, I have 25 devised a common battery system, and have provided therefor a series of indicating keys which serve the purpose of connecting the various parties on the line, of operating their signal bells, of cutting off the ringing 30 current, and finally of switching on the talking current. These keys are arranged in sets and are so constructed that when one key is depressed to complete a circuit any other key of the set which happens to be depressed at that time, is released and is returned to normal position. The keys are 35 adapted to assume three positions. The lowermost position of any key closes a master contact; the intermediate position establishes talking communication and also indicates the station that is connected, while the 40 third position is the normal position of disconnection.

A further object of my invention is to so 45 arrange an intercommunicating telephone set that by the addition of an extra key and signaling devices one of the stations on the line may serve as an attendant station in private branch exchange work, the extra key 50 serving to hold the main trunk while the attendant calls the subscriber wanted.

A further object of my invention is to provide the extra trunk holding keys at the attendant station when the system is designed 55 for private branch exchange work, with au-

tomatic means for breaking the circuit through the contacts of the extra key as soon as the called party responds and takes up the trunk, in case the attendant should neglect to release the trunk holding key.

My invention provides a system in which the hook switch is so wired that the key circuits of a particular station are cut off when that station is not in use, thus rendering it unnecessary to restore the keys when through 65 talking.

Other objects and advantages of my invention will be more clearly set forth in the specific description of the system as set forth in the body of the specification.

My invention is illustrated in the accompanying drawings in which—

Figure 1 is a side elevation showing a set of switch keys. Fig. 2 is an end view, partly in section, showing the construction of a 75 key. Fig. 3 is an end view showing the master ringing contact. Fig. 4 is a diagrammatic view showing the general arrangement of my improved intercommunicating system. Fig. 5 is a diagrammatic view 80 showing the arrangement at the attendant's station of an automatic disconnect mechanism for the trunk holding key.

Referring to the drawings, 1 designates a rectangular frame provided with push buttons 2 disposed on the ends of the rods 3 and adapted to reciprocate in openings 4 in the frame 1. Spiral springs 5 arranged on reduced portions of the rods 3 serve to keep said rods in a normally raised position. Journaled in slots 6 in the rods 3 are the cam rollers 7 of insulating material, while projecting laterally from said rods are the pins 8 and 8'. Pivoted on the frame 1 at 9 and 9' are the inturned ends 10 and 10' of 95 the locking plate 11 which is provided with openings 12 for the purpose of receiving the pins 8 and 8' to lock the keys 2, in a manner hereinafter described. At one end of the frame 1 there is located a master contact 100 which is designed to be closed on the depression of any one of the keys to its lowest position and which is opened again on the release of the keys. Reference to Figs. 1 and 3 will show that the plate 11 has a hook-like 105 extension 13 adapted to bear on an insulating bearing member 14 carried by a contact spring 15, the latter being provided with a contact point 16. It will be seen that on the depression of any one key the pin 8' will 110

come in contact with the cam surface 12' on the locking plate 12 while on further depression of the key the upper pin 8 which is longer than the lower pin will engage the 5 cam surface 12' and tilt the locking plate backward from the frame. The upper pin, however, never gets below the cam surface on account of the button 2 engaging the upper surface of the frame. The movement of 10 the rod 3 is sufficient, however, when the key has been depressed to its lowest position and the pin 8 has engaged the cam surface 12', to actuate the locking plate as above explained to cause the hook-like extension 13 15 to bear against the spring 15 and to force its contact 16 against the anvil 17. This contact will be kept closed as long as any one of the keys is depressed to its limit, but owing to the action of the spring 15 the locking 20 plate will be returned to its original position when pressure on the button is relieved. The key however will not return to its original position but will assume an intermediate position due to the fact that the pin 8' engages the edge of the opening 12 which locks the key in position. When another key is 25 depressed the locking plate 11 is forced backward by means of the pins 8 and 8' and the first key which had been locked in its intermediate position is now released and assumes its normal position.

It will be readily seen from the above description that on depression of any one of the keys to its lowest position the master contact will be closed and any other key will be released. As clearly shown in Fig. 1 the cam rollers 7 on coming into contact with the springs 18 will force the latter against their anvils 19 and thus complete circuits 40 through these parts. It will be noted that in the intermediate position of the key, the latter contacts are closed.

I have described above a set of keys that is peculiarly adapted for use in an intercommunicating telephone system. It will be understood that other specific forms of keys could be used without departing from the spirit and scope of my invention and I therefore do not wish to limit myself to the specific construction herein described.

The arrangement of my improved circuits is well illustrated in Fig. 4, in which the ringing battery is shown at R, and the talking battery at T. Connecting the various 55 stations on the line with the ringing battery are the conductors r and r' . The conductors $a-a'$, $b-b'$, $c-c'$ serve for the talking circuits of the stations 1, 2 and 3. In circuit with each of these conductors are the choking coils $x_1-x_2-x_3$. Each station is provided with a set of keys similar to the ones described heretofore, each key being numbered to correspond with a particular station on the line. Included in each set is a 60 trunk key which is available when the trunk

lines t and t' are used for the talking circuit in private branch exchange work. These keys are designated on the drawings as K_1 , K_2 , K_3 . The master ringing contact of each set is shown at C_1 , C_2 , C_3 . The connections between the various parts are plainly shown in the drawing and these parts include the ordinary receivers R_1 , R_2 , R_3 normally supported on the switch hooks S_1 , S_2 , S_3 and connected in the bridge wire 70 of a Wheatstone bridge having choke coils in two of its arms and balancing non-inductive resistances in the other two, the above arrangement being for the purpose of preventing the battery currents from affecting 75 the receiver while permitting the voice currents to pass through it. T_1 , T_2 , T_3 are the transmitters and B_1 , B_2 , B_3 are the signal bells.

The operation of my invention is as follows: When a party at any one of the stations desires communication with another station, for instance, if the party at station 1 wishes communication with station 3, he presses the key 3 to its lowest limit, closing 80 the master ringing contact C_3 . Current now flows from the ringing battery R over the following path: R , r , d_1 , C_3 , e_3 , f_3 , y_3 , g_3 , x_3 , i_3 , B_3 , j_3 , S_3 , k_3 and r' . The party at station 3 responds by pressing his home button, *i. e.*, the button numbered the same as the station at which it is located. He then takes his receiver off the hook switch, thereby completing the talking circuit at his end of the line through the contacts on the upper side of the hook switch S_3 while the party at station 1 does the same at his end of the line. Both telephones are now bridged across the bus-circuit from the common battery T. The following circuit is completed through 105 the telephone at station 3: T , x_3 , c , l_3 , m_3 , n_3 , o_3 , T_3 , R_3 , S_3 , p_3 , e_3 , f_3 , y_3 , h_3 , c' and x_3 . The circuit through the telephone at station 1 is completed as follows: T , x_1 , c , l_1 , m_1 , n_1 , o_1 , T_1 , R_1 , S_1 , p_1 , e_1 , f_1 , y_1 , g_1 , c' and x_1 . As 110 has been before stated, when the pressure on a key is released it returns only part way, thus serving as an indication of the station connected. This slight movement of the button is sufficient however to open up the master ringing contact and leave the system ready for talking. It will be seen that it is not necessary to restore these keys when through talking as the hook switch is so wired that the circuits controlled by the 115 keys are cut off when the station is not in use and the latter is then in condition to receive a call from any of the other stations. It will be noted also that when the subscribers are talking it is impossible for ringing current to pass through their telephones and to interfere with their conversation since the retraction of the button to its intermediate position opens up the master ringing contact and thus cuts off the ringing 120

125

battery. The depressed keys however are locked in their retracted or intermediate positions and the circuits controlled through these keys, in this position, are maintained 5 closed as long as desired. As soon as the receivers have been again hung up the line is restored to its normal condition.

This intercommunicating telephone system is particularly adapted for private 10 branch exchange work, as a trunk circuit to the main exchange can be multiplied through all the intercommunicating telephones and can terminate on buttons the same as the regular stations. When the system 15 is thus arranged it is desirable to have one of the telephones serve as an attendant or operator station, an extension bell E being bridged across the trunk circuit in series with the condenser F to serve as a signal for 20 incoming calls. In the drawing I have shown station 1 as the attendant station. The attendant answers the signals by pressing the trunk button K₁. As soon as the party desired is known, the trunk can be 25 held by means of a special key V provided with a retardation coil W; while the attendant operator calls up the desired station by means of the proper button. As soon as the party responds and takes up the trunk the 30 attendant releases the holding key, and conversation is now carried on over the trunk line between the two local stations through the main exchange in the same manner as described with reference to the stations in 35 the local lines. If the attendant operator at station 1 should neglect to release the holding key V it would of course prevent the releasing of line signals at the main exchange after the parties are through talking. To 40 provide against such a contingency I have devised a means for automatically disconnecting the trunk coil from the circuit when the receiver at the attendant station is placed on its hook. This device is clearly shown in 45 Fig. 5. In this figure there is shown an extra contact s₁ above the hook switch and adapted to be closed by the latter when the receiver is removed from the hook. The operator's trunk holding key is adapted in this 50 instance to close a contact on one side only, viz., the contact at t₁. It will be noted that after the receiver is removed and the trunk holding key, which in this case is made non-locking, is depressed, the circuit from the 55 ringing battery is closed through the following path: R, r, d, q₁, locking relay H, u₁, t₁, v₁, k₁, r' and back to battery. The relay H pulls up its armatures at both ends and the circuit through the winding of said 60 relay is now locked through the contact w₁, conductor z₁, and contact s₁. The contact r₁ is now closed and the circuit through the retardation coil W is completed. When the attendant hangs up her receiver the locking 65 circuit is broken at the contact s₁, the mag-

net of the relay H lets go and the circuit through the retardation coil is broken, thus permitting the trunk line signals at the main exchange to be released when the talking party hangs up.

It will be seen from the above description that I have provided a system in which the different stations may be connected through comparatively simple means. The operation of the spring controlled push keys in 70 the automatic releasing of adjacent keys, in the closing of the master ringing contact and in the opening of the latter when the pressure is relieved, while maintaining the talking circuits closed in the locked intermediate position, is particularly advantageous in an intercommunicating system where the parties at each station necessarily have to assume part of the duties of an operator in getting the desired connections. 75 The pressing and releasing of the keys is an operation much more simple than the use of the ordinary switches or of the cords and the necessary jacks. 80

I am aware that changes in detail may be 85 made in both the apparatus and the circuits of my system without departing from the spirit of the invention. All such changes are within the scope of my claims.

Having thus described my invention what 90 I claim and desire to secure by Letters Patent is—

1. In an intercommunicating telephone system, the combination of a plurality of stations, conductors extending between such stations, means for signaling each station by each of the other stations, means for establishing a talking condition between any two of such stations, a common battery trunk line extending from an exchange to such stations, signaling means at one of such stations adapted to be operated from the exchange, a key at such last named station for connecting such station to the trunk line, a self restoring key at such station for closing 100 an electrical path between the conductors of the trunk line, and means for maintaining a path for electricity after the release of said self restoring key and during the calling and connecting of another of such stations to the 105 trunk line.

2. In an intercommunicating telephone system, a main exchange, trunk lines connecting said main exchange with a plurality of groups of local substations connected by 110 local lines and having a common ringing circuit, each substation having a set of push keys controlling said trunk and local lines and one of said stations of each group serving as an attendant's station and being provided with a signal bell adapted to be rung from the main exchange, means for ringing up any one station of a group, on the manipulation of a key at the attendant's station, a self restoring push key bridged across the 115 120 125 130

ringing circuit and having in series therewith a locking relay adapted to control a trunk holding circuit, means for breaking the circuit through said locking relay when the attendant hangs up her receiver, thus disconnecting the trunk holding circuit, and means for establishing talking communication between any two substations of different groups in the system by the manipulation of the trunk key at said stations.

3. In an intercommunicating telephone system, a main exchange, trunk lines connecting said main exchange with a plurality of groups of local substations connected by local lines and having a common ringing circuit, each substation having a set of push keys controlling said trunk and local lines and one of said stations of each group serving as an attendant's station and being provided with a signal bell adapted to be rung from the main exchange, means for ringing up any one station, of a group on the manipulation of a key at the attendant's station, a self restoring push key bridged across the ringing circuit and having in series therewith a locking relay, a trunk holding circuit controlled by the armature on said locking relay and comprising a retardation coil, means actuated when the attendant restores her hook switch to normal condition, for breaking the locking relay circuit, said trunk holding circuit being interrupted when said locking relay circuit is broken, and means for establishing talking communication between any two substations of different groups in the system by the manipulation of the trunk key at said stations.

4. In an intercommunicating telephone system, a main exchange, trunk lines connecting said main exchange with a plurality of groups of local substations connected by local lines, each substation having a set of push keys controlling said trunk and local lines and one of said stations of each group serving as an attendant's station and being provided with a signal bell adapted to be rung from the main exchange, means for ringing up any one station of the group on the manipulation of a key at the attendant's station, a self restoring push key at the attendant's station for closing the trunk circuit and thus holding the trunk line until the called station responds, automatic means operating to disconnect the trunk holding circuit when the attendant hangs up her receiver, and means for establishing talking communication between any two substations of different groups in the system by the manipulation of the trunk key at said stations.

5. In an intercommunicating telephone system, a main exchange, trunk lines connecting said main exchange with a plurality of groups of local substations connected by local lines and having a common ringing circuit, each substation having a set of push

keys controlling said trunk and local lines and one of said stations of each group serving as an attendant's station and being provided with a signal bell adapted to be rung from the main exchange, means for ringing up any one station of a group on the manipulation of a key at the attendant's station, a trunk controlling circuit comprising a self restoring push key and a locking relay, said key and relay being bridged across the ringing circuit, and the armature of said relay adapted to close and open a trunk holding circuit provided with a retardation coil, and a contact at the attendant's hook switch adapted to be opened when the attendant hangs up her receiver, thus breaking the circuit through the locking relay and disconnecting the trunk holding circuit.

6. In an intercommunicating telephone system, a plurality of stations, conductors extending between such stations, means at each station for signaling a desired one of the remaining stations, means for establishing a talking condition between such two stations, a common battery trunk line extending from an exchange to such stations, signaling means at one of such stations adapted to be operated from the exchange, a key at such station for closing an electrical path between the conductors of the trunk line, means for maintaining the closure of such path after the release of the key during the calling and connecting of another of such stations to the trunk line, the return of the receiver to the receiver hook at such first station serving to interrupt such electrical path.

7. In an intercommunicating telephone system, a plurality of stations, conductors extending between such stations, means at each station for signaling a desired one of the remaining stations, means for establishing a talking condition between such two stations, a common battery trunk line extending from an exchange to such stations, signaling means at one of such stations adapted to be operated from an exchange, a relay at such station adapted to close an electrical path between the conductors of the trunk line and to close a locking circuit through its energizing winding when operated, and a key at such station adapted to operate such relay, the closure of such electrical path serving to hold the trunk connection during the calling and connecting of another of such stations to the trunk line, the return of the receiver to the receiver hook at such first station serving to interrupt such locking circuit.

In testimony whereof I affix my signature 125 in presence of two witnesses.

RAY H. MANSON.
